PHONOGRAPH

Arthur G. Zimmerman, Westmont, N. J., assignor to Radio Corporation of America, a corporation of Delaware

Application August 31, 1935, Serial No. 38,683

15 Claims. (Cl. 274—9)

This invention relates to phonographs, and more particularly to means for insuring a turntable supported disc record from slipping on the turntable during playing thereof.

5 It is well known that, in order to obtain satisfactory reproduction of sound from a record, the record must move at uniform speed relative to the sound translating device. Thus, in the case of a phonograph employing disc records, the turntable and the record supported thereby must rotate at uniform speed with respect to the pick-up.

In the copending application of Benjamin R. Carson and myself, Serial No. 13,796, we have disclosed a system for driving the turntable of a phonograph with such uniform speed that any slight variations which may occur therein produce no noticeable undesirable effects. However, it occasionally happens that the record supported 10 by the turntable slips slightly thereon, and this, of course, results in a noticeable variation in the pitch of the reproduced sound.

The primary object of my present invention is to provide an improved driving connection between the record and the turntable whereby the aforementioned difficulty is overcome.

More specifically, it is an object of my invention to provide a novel record driving mechanism whereby the record will be driven positively from 15 both its surfaces.

It is a further object of my invention to provide, for conventional disc records, an improved record drive whereby a turntable supported record will be driven not only from the turntable 20 but from the turntable spindle as well.

Another object of my invention is to provide an improved record weight which will not only press the record against the turntable, but which will have driving engagement with the turntable 25 spindle and which can be quickly and easily applied to conventional phonographs.

Still another object of my invention is to provide an improved record weight as aforesaid which will be simple in construction and highly 30 efficient in use.

In accordance with my present invention, I provide a record weight with a bore to fit over the turntable spindle and provide means either within or in association with said bore whereby 35 the weight may have driving engagement with the spindle. The record weight is also provided with a record engaging surface of such nature and so arranged that it will have frictional connection with the top surface of the record. Thus, the record is driven by the turntable at its turn-

table contacting surface and by the spindle driven weight at its opposite surface. The record engaging surface of the weight may, if desired, be so arranged, that a partial vacuum is created between it and the record, whereby the weight grips the record firmly to assist in rotating it without slipping on the turntable.

The novel features that I consider characteristic of my invention are set forth with particularity in the appended claims. However, the invention itself, together with additional objects and advantages thereof, will best be understood from the following description of two specific embodiments thereof, when read in connection with the accompanying drawing in which

Figure 1 is a view, partly in section, of one form of my improved record weight,

Figure 2 is a sectional view taken on the line 2—2 of Figure 1,

Figure 3 is a detail perspective view of a plate 20 for providing driving connection between the spindle and the record weight according to one form of my invention.

Figure 4 is a fragmentary, detail perspective of the spindle, and

Figure 5 is a fragmentary, sectional detail showing a modified form of my invention.

Referring more specifically to the drawing, wherein like reference characters designate corresponding parts throughout, there is shown a 30 motorboard 1 which supports a motor 3 for driving a turntable spindle 5 on which is supported a turntable 7. The turntable has driving engagement with the spindle 5 through the cross pin 9 which is received by the turntable hub 11, and it is provided with the usual felt surface (not shown), on which a record R rests, the felt serving to provide a frictional drive between the record and the turntable. The construction thus far described is more or less conventional and is 35 subject to the disadvantages heretofore pointed out.

To insure against slipping of the record R on the turntable 1, I preferably form the protruding end 5a of the spindle 5 of a non-circular shape 45 and cause it to drive a record weight 13 which rests on the record R. The weight 13 is made of a mass of metal and is provided with a central bore 15 for receiving the spindle end 5a when it is placed on a record, while a driving plate 17, secured to the mass 13 by the screws 19 and provided with an aperture 21 of a configuration corresponding to the shape of the spindle end 5a, serves to provide a driving connection between the spindle 5 and the mass 13. In the particular 50 55

embodiment illustrated in Figs. 1 to 3, the end 5a is shown square with the corners 5b thereof rounded off somewhat to prevent injury to the hands and to the record, the aperture 21 being also square and of a dimension to snugly fit over the end 5a. The spindle end 5a and the aperture 21 may, obviously, be formed of any other polygonal or other suitable shape (for example, elliptical), it being merely necessary that a positive driving coupling be effected between the spindle 5 and the driving plate 17.

To the bottom of the mass 13 is affixed a base 23 having a greater diameter than the mass 13, a resilient disc 25 of substantially equal diameter being interposed between the driving plate 17 and the base 23. The disc 25 is preferably formed of live rubber and is preferably held against the base 23 only by the cooperative action of the screws 19 and the plate 17 and without the use of any cement or other adhesive. By making the driving plate 17 concentric with the base 23 and of much smaller diameter than that of the disc 25, the peripheral portion of the live rubber disc will be free to readily accommodate itself to any irregularities in the surface of the record which it engages under the pressure of the mass 13, and a firm gripping action will result. In some cases, as where the base 23 and the disc 25 are dished slightly away from the record R, as shown in Fig. 30 1, a partial vacuum is created when the weight 13 is pressed against the record, thereby enhancing the gripping action between the disc 25 and the record. In any event, it will be seen that this provides an additional drive for the record R and 35 that the record is prevented from slipping on the turntable because it is driven from its lower surface by the turntable itself and from its upper surface by the weight 13.

The form of my invention heretofore described 40 requires that the spindle end 5a and the aperture 21 be specially formed. For conventional phonographs employing the usual cylindrical spindle, the modification shown in Figure 5 may be used. In this form, the plate 17 is provided with a plurality of gripping members, such as springs 27, which extend into the bore in converging relation and which firmly grip the spindle 5 to provide the necessary driving connection between the spindle and the weight.

Although I have shown and described several 50 embodiments of my invention, I am fully aware that many modifications thereof and changes therein may be made without departing from the spirit of the invention. I desire, therefore, that my invention shall be limited only by the prior art and by the spirit of the appended claims.

I claim as my invention:

1. In a phonograph, the combination of a driving member, a turntable having driving engagement therewith, a record supported on said turntable, and means resting on said record and having driving connection with said member, said means also having gripping engagement with said record whereby said record is adapted to be driven both by said turntable and by said means.

2. In a phonograph, the combination of a driving member, a turntable having driving engagement therewith, a record supported on said turntable, and a record weight resting on said record and having driving connection with said member, said weight having gripping engagement with said record whereby said record is adapted to be driven both by said turntable and by said weight.

3. In a phonograph, the combination of a motor 75 driven spindle, a turntable having driving en-

gagement therewith, a record supported on said turntable, and a record weight resting on said record and having driving connection with said spindle, said weight having gripping engagement with said record whereby said record is adapted to be driven from said spindle through one surface thereof by said weight and through its other surface by said turntable. 5

4. The invention set forth in claim 3 characterized in that the spindle has a non-circular portion and said weight has a member provided with a correspondingly shaped aperture adapted to receive said non-circular portion whereby to provide driving connection between said spindle and said weight. 10

5. The invention set forth in claim 3 characterized in that the spindle has a substantially square portion at its upper end and said weight has a driving plate affixed thereto, said plate having a substantially square opening therein adapted to receive said square portion of the spindle whereby to provide driving connection between said spindle and said weight. 15 20

6. The invention set forth in claim 3 characterized in that the weight has a resilient member affixed thereto for providing gripping engagement with the record. 25

7. A record weight comprising a mass having a bore therein extending from its base whereby the weight may be fitted over a phonograph spindle, 30 a driving plate secured to said base for providing driving connection between said mass and said spindle, and a resilient member on said base for engaging a phonograph record threaded on said spindle whereby to provide gripping engagement 35 between said mass and said record.

8. The invention set forth in claim 7 characterized in that said resilient member comprises a disc of live rubber.

9. The invention set forth in claim 7 characterized in that the base of said mass is of greater diameter than the body portion thereof, characterized further in that said driving plate is concentric with said base and has a much smaller diameter than the base, and characterized still 45 further in that said resilient member comprises a disc of live rubber of a diameter substantially equal to that of said base, said rubber disc being held against said base solely by said driving plate whereby the peripheral portion of said rubber disc 50 is free to snugly engage the record in firm gripping engagement therewith. 40 50

10. The invention set forth in claim 7 characterized in that said driving plate is provided with a spindle gripping member. 55

11. The invention set forth in claim 7 characterized in that said driving plate is provided with a plurality of resilient spindle gripping elements adapted to cooperate mutually to grip said spindle. 60

12. The invention set forth in claim 7 characterized in that said driving plate is provided with a plurality of resilient spindle gripping elements extending into said bore in converging relation. 65

13. In a phonograph, the combination of a turntable spindle having an end portion of non-circular shape, and a record weight, said record weight having a central bore for receiving said end portion and having a driving plate affixed thereto, and said driving plate having an aperture therein of corresponding shape to receive said spindle end portion whereby to provide driving connection between said spindle and said weight. 70

14. The invention set forth in claim 13 char- 75

acterized in that said spindle end portion is substantially polygonal and said aperture is correspondingly substantially polygonal, said driving plate being affixed to the base of said weight with its aperture substantially coaxial with said base.

5. 15. The invention set forth in claim 13 char-

acterized in that said spindle end portion is substantially square and said aperture is also square, said driving plate being affixed to the base of said weight with its aperture coaxial with said bore.

ARTHUR G. ZIMMERMAN.
